UNITED STATES PATENT OFFICE.

HOMER PAYNE CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed September 26, 1923. Serial No. 664,885.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Con-
ductor Supports, of which the following is
a specification.

My invention relates to supports for con-
10 ductors and particularly to that class of
support by means of which the adjacent
ends of two trolley sections are held in fixed
but insulated relation to each other.

The object of my invention is to provide
15 a device as stated above which is particu-
larly adapted to use in mines where the
mine roof is low and it is desired to place
the trolley conductor as near the roof as
possible with safety, and this object is ac-
20 complished by producing a device of as lit-
tle vertical height as possible, consistent
with requirements of strength, insulation,
etc., and to so place the supports secured to
the device, and by means of which it is se-
25 cured to the roof supports, that the upper
edge of the device can be brought into close
proximity to the mine roof. My invention
resides in the new and novel construction,
combination and relation of the various
30 parts hereinafter more fully described and
shown in the accompanying drawing.

In the drawing:

Figure 1 is a top plan view of my invention.

Fig. 2 is a side view in elevation.

35 Fig. 3 is an end view.

Fig. 4 is a longitudinal sectional view of
the attaching means for securing the de-
vice to the overhead supports and is taken
on the line 4-4 of Fig. 1.

40 Fig. 5 is a sectional view on the line 5-5
of Fig. 4.

In the preferred form of the construction
embodying my invention I employ an insu-
lating member 1, preferably of wood, al-
45 though other insulating material, such as
fiber, etc., may be used. To the ends of
the member 1 I secure connecting members
2 secured to the member 1 by means of the
bolts 3 and each provided with a longitudi-
50 nally extending recess to receive the ends of
the trolley wire 4 which is held in the re-
cess by means of the set screws 5. The in-
ner ends of the connecting members 2 are
spaced apart and the space between the ends
55 is filled with an insulating runner piece 6,

the lower surface of which conforms to the
lower surface of the members 2 thereby
giving a smooth and unobstructed path for
the current collector. Other means may be
used for the member 6, such as a metal run-
60 ner piece spaced from the members 2 or a
pivoted member which may be moved into
or out of position between the members 2.

The device is provided with brackets 7,
one at each end by means of which it is sup-
65 ported from the roof by means of well
known roof supports such as insulated
hangers held in place by lag screws, expan-
sion bolts, etc. The brackets are secured
70 to the member 1 by means of the bolts 3. In
order to support the device as near the
roof as possible the projecting ends of the
brackets 7 are set low upon the device so
that they project longitudinally at a point
75 between the upper and lower face of the
member 1. It has been the custom in the
past to mount the means by which the de-
vice is supported from the roof to the upper
face of the member 1 either at the center or
80 at the ends, but this method means a greater
distance between the trolley wire 4 and the
roof of the mine, which is objectionable.
To overcome this defect, I have so mounted
the brackets 7 that the upper edge of the
85 member 1 may be positioned above the up-
per edge of the outer ends of the brackets 7.

The end of the bracket 7 is provided with
a novel construction, in that the bracket is
provided with an elongated slot 8 in which
is loosely mounted a rotatable and slid-
90 able nut 9. The nut is provided with a threaded
recess 10 by means of which the nut is se-
cured to the roof support by rotation of the
nut 9. To secure the nut 9 to the member
7 the upper end of the nut is provided with
95 a thin annular flange or lip 11 which orig-
inally stands upright. A washer 12 of the
shape shown is placed in position as shown,
together with the member 9, and by suitable
tools the annular flange or lip 11 is rolled
100 outwardly, thereby locking the members 9
and 12 together. A slight space is left be-
tween the nut 9 and the member 7, as indi-
cated at 13, which permits the rotation of
the nut 9 and its longitudinal movement in
105 the slot 8. This longitudinal movement per-
mits of adjustability of the supports, and is
found of advantage for the reason that it
is not always possible to secure the roof sup-
ports with an exact separation of centers,
110

and when such is the case it is a difficult and expensive matter to properly secure the device in place. If desired, the slot 8 may be made a circle thereby permitting lateral, 5 as well as longitudinal adjustment.

By giving the upper end faces of the member 1 a greater bevel and by properly shaping the bracket member 7, the projecting end of the member 7 can be brought still 10 lower, in fact, as low as necessary clearances between the members 9 and 5 will permit.

Modifications will readily suggest themselves to others skilled in the art, therefore, I do not wish to be limited otherwise than 15 by my claims.

I claim:

1. An article of manufacture comprising an insulating member, conductor connecting members secured to the ends thereof, means 20 to secure conductors thereto and support members secured to the insulating member and projecting in a longitudinal direction and intermediate the upper and lower faces thereof.

2. An article of manufacture comprising an insulating member, spaced conductor connecting members secured to the ends thereof and provided with means to receive conductors, means positioned between the inner 30 ends of the conductor connecting members to provide an under-run for a current collector and support members secured to and projecting from each end of the insulated member and projecting intermediate the 35 upper and lower faces thereof.

3. A section insulator of the class described for trolley conductors provided with spaced and insulated projecting supporting means which projects from a point intermediate the upper and lower edges thereof.

4. A section insulator of the class described for trolley conductors provided with projecting and swivelly mounted supporting means which projects from a point below the upper limit thereof.

5. A section insulator of the class described for trolley conductors provided with a rotatable support member adjustable in a plane parallel to the plane of the trolley 50 wire.

6. An article of manufacture comprising an insulating member, spaced conductor connecting members secured thereto, means positioned between the inner ends of the 55 connecting members to permit a current collector to pass from one connecting member to the other connecting member and a plurality of spaced, rotatable and longitudinally adjustable support members secured to the insulating member.

7. A section insulator of the class described for trolley conductors provided with a plurality of spaced and adjustable supporting means projecting in the direction 65 of the trolley conductor.

8. A section insulator of the class described for trolley conductors provided with a plurality of spaced, rotatable and longitudinally adjustable supporting means.

9. A section insulator of the class described provided with a plurality of depressed, insulated, spaced and projecting supporting members.

10. A section insulator of the class described provided with a plurality of spaced 75 and projecting supporting members and each member provided with an adjustable means to secure the insulator to an overhead support.

11. A section insulator of the class described provided with supporting means comprising a part secured to the insulator, a projecting member, means mounted on the projecting member for attachment to an overhead support, the said means having its 80 upper face below the extreme upper face of the insulator and rotatable about a vertical axis.

12. A section insulator comprising an insulating beam, spaced conductor connecting 90 members secured to the beam, means to provide a running surface for a current collector between the connecting members, the insulating beam having its upper surface at its ends beveled downwardly and outwardly in a longitudinal direction and a support member mounted on each beveled surface and secured to the beam.

13. A section insulator comprising an insulating beam, spaced conductor connecting 100 members secured to the beam, means to provide a running surface for a current collector between the connecting members, the insulating beam having a portion of each 105 of its ends depressed and a support member mounted on each depressed portion and secured to the beam.

14. A section insulator comprising an insulating beam, spaced conductor connecting members secured to the beam, means to 110 guide a current collector from member to member, a pair of supporting members secured to the beam and having a depressed portion relative to the top of the beam and rotatable means mounted on each depressed portion for securing the device to overhead supports.

15. A section insulator comprising an insulating beam, spaced conductor connecting 115 members secured to the beam, means to provide a running surface for a current collector from member to member and supporting means for securing the device to an overhead support and provided with a projecting member, an opening therein and a rotatable member mounted therein and provided with means for attachment to the overhead support.

In testimony whereof I affix my signature.
HOMER PAYNE CHANDLER.
